IMPROVED MODE OF CONSTRUCTING BUILDINGS.

FREDERICK O. ROGERS, OF NILES, MICHIGAN.

Letters Patent No. 60,425, dated December 11, 1866.

The Schedule referred to in these Letters Patent and making part of the same.

TO ALL WHOM IT MAY CONCERN:

Be it known that I, FREDERICK O. ROGERS, of Niles, in the county of Berrien, and State of Michigan, have invented a new and improved mode of constructing Wooden Buildings; and I do hereby declare that the following is a full and exact description thereof, reference being had to the accompanying drawings, making part of this specification, in which—

Figure 1 is a front elevation of a building constructed after my improved method.

Figure 2 is a transverse vertical section of the same.

Figure 3 is a horizontal section of a portion of the wall as constructed with a hollow space or non-conducting air chamber therein.

Figure 4 is a view showing the manner of uniting the walls at the corners.

Figure 5 a view representing the manner of joining the sections.

Like letters of reference indicate corresponding parts in all the figures.

My invention has for its object the construction of wooden buildings, portable and stationary, in such a manner as to insure the requisite strength, with less material than is ordinarily required, and without the necessity of a frame, thereby saving both in labor and cost as well as weight and bulk; and the invention consists in constructing the walls of lath, or other strips or battens of wood, joined together in series of two or more, to form the thickness of the wall, one series being of transverse direction to the other, and secured together in any suitable manner. The strips or battens may vary in size and proportion according to convenience of circumstances, from building laths, which are four feet long, one and a half inches wide, by three-eighths inch thick, to a considerably greater length, breadth and thickness; but it is preferable that the battens should be thin, to economize material, and narrow, to prevent expansion and contraction by wet and heat, as by my method great strength is secured in walls that are very thin and light, and the expansion and contraction of a wall of any size is no more than that of one of its battens. A series of these battens, *a* fig. 2, corresponding as nearly as may be to the size of one side of the building to be erected, are laid with their edges in contact, and if the laths are short, the first or bottom course should vary in length, so as to break joints. Upon these another series *b* is laid, the longitudinal direction of which is transverse to the first series, (with joints broken lengthwise, also, if short;) upon this a third series *c* is again laid, having a direction corresponding with the first, (and breaking joints with the first series both ways) which is preferably vertical when the wall is erected; and upon this a fourth and (ordinarily) the last series *c'* is laid, taking care in this to mitre the ends of the battens, if short, as shown at *a*, figs. 4 and 5, and to cover the joints both ways between the battens of the series last previously laid. When this is done the whole of the series are secured firmly by nailing, and clinching the points of the nails, which should be long enough for the purpose, on the inner side. Any other suitable means of fastening the parts together may be used, as screws, wooden pins, &c. If the building be of small size, two thicknesses of the lath or battens may be sufficient, and the number may be increased in proportion to the dimensions of the house. The walls having been formed in this manner, and a suitable foundation, with wooden sills *d*, fig. 2, provided, the sides are placed in position, and nailed or spiked to the sills, and also to the plates or girts, *ff*, on which rest the joists *g* for the floor *j*. The corners of the sills and plates, as also of the walls, may be held together by angular plates *e e*, securely nailed or spiked to the timbers. A shoulder *h* is preferably left or formed in the side walls previous to setting on the sills *d d*, to form a stable support for the weight of the sides. In forming the corners of the wall the end and side walls are interlapped or dovetailed easily, by passing each alternate lath *x* of one of the middle series on the side wall, out, between and past the corresponding one *y* of the end wall, and *vice versa*, as shown in fig. 4. The sections of the wall, when it is formed in sections, may also be made to interlock or interlap—the laths or battens of one of the middle series breaking joints or interlapping when the sections are united, as shown in fig. 5. The roof is formed in the same manner as the sides, by joining the series with one or more of the interior, transverse to the outer ones. The strips of the two exterior series of the roof should carefully break the joints, and be mitered, if short battens are employed, and should be laid with a stratum of pitch or water-proof cement between, as at *i i*, to prevent the absorption of moisture. Ridge strips *k*, are applied in the usual manner at the angle of the roof. The walls so formed are capable of being divided by the saw to form openings for the doors, which require no frame or casing, and the parts removed may be hinged directly to the wall, as shown

at *m m*, fig. 1. The openings for windows may be formed in the same manner, or be left out in constructing the walls to save material. The principle of constructing the wall of transverse series of strips secures the advantage of much strength and rigidity with a thin or light wall, and the prevention of warping or springing in the sides, as will be readily understood. This enables door and window frames, studding, &c., to be dispensed with without impairing the strength of the building; and by this means four-fifths of the labor is dispensed with, making this kind of tenement exceedingly cheap, and, from being rapidly erected, especially adapted to newly settled localities, where lumber is abundant and labor scarce, and to being transported ready made to places where lumber and labor are scarce. This principle also adapts this method to the erection of portable houses, as the walls may be formed in sections and united by metallic plates, or hinged, as shown at *l l*, fig. 1, and thus be easily taken down and stored in a small compass for transportation; and even when erected for a permanent building, they may afterward be sawed into sections, removed, and re-erected without detriment to their strength or appearance. To secure the better results for dwellings, of warmth in winter and coolness in summer, a space may be left in the interior of the wall, by inserting strips of "furring," *p p*, fig. 3, to form non-conducting air spaces, *o o*. This materially strengthens the wall by making it thicker, without adding much to its weight. Walls so formed exclude the air and moisture, and leave few interstices to harbor insects. They may be finished by painting and sanding the exterior, and by papering the interior, dispensing entirely, if desired, with plastering.

I do not claim broadly the union of two or more thicknesses of boards, or planks, crossing one another, for making doors, partitions, &c.; but,

What I claim as my invention, and desire to secure by Letters Patent, is—

Constructing the walls and roofs of wooden buildings, whole or in sections, by the union of two or more series or layers of laths or battens, crossing each other transversely, the said walls and roofs, or sections thereof, being united so as to form a firm structure without the use of additional walls, frame-work or braces, substantially as and for the purposes herein specified.

In testimony whereof I have hereunto signed my name in the presence of two subscribing witnesses.

F. O. ROGERS.
